(57) **CLAIM**

The ornamental design for a vegetable peeler, as shown, and described.

DESCRIPTION

FIG. 1 is a perspective view of a vegetable peeler;
FIG. 2 is a front view thereof;
FIG. 3 is a rear view thereof;
FIG. 4 is a right elevation view thereof, the left elevation view being a mirror image thereof;
FIG. 5 is a top plan view thereof; and,
FIG. 6 is a bottom plan view thereof.
The broken lines in the drawings depict portions of the vegetable peeler that form no part of the claimed design.
